UNITED STATES PATENT OFFICE

ALFRED C. DANKS, OF CLEVELAND, OHIO

PULVERIZER

Application filed September 5, 1929. Serial No. 390,515.

The invention relates to pulverizers, and more particularly coal pulverizers, although the machine may be applied to the pulverizing of rock or other solid material which it is desired to bring to a finely divided condition. Heretofore, two main types of machines have been used in pulverizing coal, the ball machine, and the impact mill. The ball mill operates at a relatively low speed and at a low cost per ton of material reduced, but has the disadvantage that all the air for combustion must be carried through the drum with the coal, otherwise, the air will not have sufficient velocity to carry the coal through the relatively large cross section of the drum. When the drum is run at low capacity, voids or pockets form in the drum, which leads to irregular burning, when the mill is used below maximum capacity. The impact mill, on the other hand, works at a high speed, as compared with the ball mill, and the impact of the arms or paddles on the fuel and the impact of particles of fuel or other particles effects the necessary pulverization. In this mill only a part of the air required for combustion is used to carry the fuel through the mill, and this feature permits a flexibility of operation, since the amount of carrying air may be regulated to correspond to the quantity of fuel being reduced. This form of pulverizer also gives complete control of the fineness of the product depending on the speed at which the material is fed to and through the mill. This form of mill has the disadvantage that the power consumed per ton of material is high compared with the ball mill, and the cost of maintenance is high due to the high speed operation and to the abrasive action of the coal upon the parts of the machine.

The object of the present invention is to provide an apparatus having the advantages of both the ball mill and the impact mill without the disadvantages of either. The apparatus uses balls, as in the ball mill, and operates at a relatively slow speed. At the same time provision is made for controlling the flow of coal and air through the drum in such manner that only a small proportion of the total air required for combustion is used as carry-

ing air. This gives the same flexibility of operation as with the impact mill and the same capability of operating at any desired capacity without any reduction in the efficiency of the apparatus or in the uniformity of fuel feed. One embodiment of the invention is shown in the accompanying drawings, wherein:

Figure 1 is a longitudinal section through the apparatus. Fig. 2 is a transverse section on the line II—II of Fig. 1. Fig. 3 is a transverse section on the line III—III of Fig. 1. And Fig. 4 is a section showing a modification.

Referring to the drawings, 1 is a cylindrical steel shell, preferably a boiler plate in which are placed a series of castings 2 made in sections so as to form a complete ring running at right angles to the axis of rotation of the pulverizer. These castings may be chilled cast iron, manganese steel, or any other material made for the purpose of withstanding abrasion. They may be placed in any desired number and of any desired diameter, and may be placed either in a straight line or they may be placed in increasing or decreasing diameters from the inlet end of the pulverizer, as seen fit.

In these grooves are placed balls A of large diameter, a sufficient number being placed in each groove to insure pulverization of the material that passes from one stage to the other, the large balls being placed near the inlet. The number of balls in these grooves and their size will depend upon the size of the unit under consideration, but the purpose of the balls and the groove is to get as large surface contact between the balls and the groove as possible rather than to depend upon the line contact that is secured in the ordinary ball mill, when the balls touch each other in the normal process of revolving with the shell.

The small amount carrying air, as it has been termed, up to possibly 10 per cent of the total required, is admitted through the feed plate 3 and through the space 4, and under some conditions, arrangements may be made for adjustments at these points to govern this air. This air, in turn, moves through

the pulverizer passing between the ends of the castings 2 and the edges of the diaphragms 5 fastened to the drum 6. The height of these diaphragms 5 may be varied to regulate the flow of air and material through the mill and thus increase or decrease the speed of material passage from one coal stage to the other. This flow causes the material to leave the first stage after it has become filled, pass over the edge of the castings through the gap 7 and fill the second stage and progress in a like manner throughout the entire unit, until it reaches the final stage. Here it passes the last diaphragm 5 and discharges through ports 9 in the drum.

The shell 1 is supported from a second larger shell 10, also of boiler plate by means of the spreaders 11 and bolts 12, and the space thus provided between the two sheets constitutes a passageway for the main body of air required for combustion, such air flowing in through the annular openings 13 and 14 and past the fan 15 through the pipe 16 to the point of combustion. The mixture of air and powdered fuel from the ports 9 is thus mixed with the main body of air flowing inward from the opening 14 to the end of the pipe 16. The fan 15 may be located at any point along the line of flow and is driven from a motor 17 mounted on the base 18, such base being in turn mounted on the main supporting base 19.

In the event of the speed becoming such that there becomes a tendency for the balls 33 to leave their grooves when carried above the center line of the mill, additional diaphragms 8a of suitable cast material and made up in sections are bolted to the drum 6 that will prevent this action. These may be substituted, if necessary, for the discs 5 and used by their varying lengths to determine the flow of material through the mill in the same manner as referred to under the discs 5.

The feed plate 3 is of the usual type comprising alternating bars and slots and is driven from the motor 20 through the gearing in the casing 21 and the speed changing means comprising the pair of stepped pulleys 22, 22, the belt 23, the worm wheel 24, the shaft 25, which carries the plate 3, and a worm carried by the shaft which carries the upper stepped pulley 22. The coal is fed from the hopper 26 by gravity past the plate 3 and through the inclined pipe therebeneath.

The shell 10 is provided with a head 27 which may be removed to permit the removal of the drum 6, such drum being carried on a separate head 28, which is removable for repairs. The outlet pipe 16 is supported on the motor base 18 by means of brackets 29, 30, with a suitable joint at 31, which allows the head 27 to revolve while the pipe 16 is stationary, suitable means being provided to make the joint tight. The drum 6 and its discs or diaphragms 5 and 8a are attached

rigidly to the shell 1 through the head 27 and revolve with the shell. The diaphragms or discs 5 and 8a may be replaced by others of varying diameters to give varying flows of air and material through the mill, depending upon the conditions encountered.

Fig. 4 shows a construction in which the discs 5 are omitted, and if desired, with the mill running at a speed low enough to avoid displacing the balls from their runways, the discs 8a may be dispensed with, the discs 5 serving by themselves to give the desired restriction to the flow of material and air through the annular space between the drum 6 and the runway castings 2.

A wear plate 32 is shown at the inlet end of the mill and is fastened to the front head 33, which is removable from the shell 1 to provide access for repairs or for replacing the castings 2.

When desired, air of high temperature or preheated air may be supplied through the inlet 13, which expedient facilitates the drying of the coal, so that a more effective pulverizing action is secured in the runways carrying the balls. It will also be understood suitable dampers may be provided when desired to control the flow of carrying air and the main body of air which is independent of the supply of carrying air.

The shell 10 and parts carried thereby are rotated from the motor 20 which drives the shaft 34 through the intermediary of suitable reduction gearing in the casing 21. The shaft 34 is provided with a gear 35 which engages the spur gear 36 secured to the shell 10. The shell 10 is also provided with bands 37, 37 engaged by a series of rollers 38, 38 carried by shafts 39 mounted in suitable bearings 40 mounted in the base casting 19. The form of feed mechanism for supplying the coal to the drum is immaterial insofar as the present invention is concerned, and the feeder 3 may be replaced with any one of the standard commercial feeders which are available, such as a belt section to which a variable speed drive may be applied.

What I claim is:

1. In combination in a coal pulverizer, a drum mounted for rotation and provided on its interior with a series of annular ball races, a set of balls mounted in each race, means for rotating the drum, means for supplying the coal to be pulverized to one end of the drum, a series of diaphragms arranged in spaced relation longitudinally of the drum with their peripheries spaced away from the walls of the drum, an air inlet to the end of the drum to which the coal is supplied, an outlet conduit leading from the other end of the drum, means for causing a flow of air therethrough to conduct from the drum a mixture of powdered coal and air, and an annular inlet passage around the drum extending longitudinally thereof and communicating with the

let at the end of the drum so that additional air is supplied at this point to the mixture of powdered coal and air flowing into said conduit.

5 2. In combination in a coal pulverizer, a drum mounted for rotation and provided on its interior with a series of annular ball races, a set of balls mounted in each race, means for rotating the drum, means for applying the coal to be pulverized to one end of the drum, a second drum inside the first drum with which the first drum communicates at its outlet end, a series of diaphragms arranged in spaced relation along the second drum with 10 their peripheries spaced away from the wall of the first drum, an air inlet to the end of the first drum to which the coal is supplied, an outlet leading from the other end of the first drum in opposition to the end of the second drum, and an annular inlet passage around the first drum extending longitudinally thereof and communicating with said outlet at the end of the drum so that additional air is supplied at this point to the mixture of powdered coal and air flowing into 15 said conduit.

3. In combination in a coal pulverizer, a drum mounted for rotation and provided on its interior with a series of annular ball races, 20 a set of balls mounted in each race, means for rotating the drum, means for supplying the coal to be pulverized to one end of the drum, a second drum inside the first drum with which the first drum communicates at its outlet end, a series of diaphragms arranged in spaced relation along the second drum with 25 their peripheries spaced away from the wall of the first drum, a mixing chamber into which the end of the second drum discharges, an air inlet to the end of the first drum to which the coal is supplied, an outlet leading from said mixing chamber in opposition to the end of the second drum, and an annular inlet passage around the first drum extending longitudinally thereof and communicating with said mixing chamber.

4. In combination in a coal pulverizer, a drum mounted for rotation and provided on its interior with a series of annular ball races, 50 a set of balls mounted in each race, means for rotating the drum, means for supplying the coal to be pulverized to one end of the drum, a second drum inside the first drum with which the first drum communicates at its outlet end, a series of diaphragms arranged in spaced relation along the second drum with 55 their peripheries spaced away from the wall of the first drum, a mixing chamber constituting an extension of the end of the first drum into which the end of the second drum discharges, an exhaust fan located in said chamber, an air inlet to the end of the first drum to which the coal is supplied, an outlet leading from said mixing chamber in opposition to the end of the second drum, and 60

an inlet leading from the atmosphere to the mixing chamber for supplying additional air thereto.

In testimony whereof, I have hereunto subscribed my name this 31st day of August, 70 1929.

ALFRED C. DANKS.
